J. A. WENDELL,
TROLLEY WHEEL,
APPLICATION FILED MAR. 7, 1921.

1,391,085.

Patented Sept. 20, 1921.

UNITED STATES PATENT OFFICE.

JOHN A. WENDELL, OF MONTGOMERY, WEST VIRGINIA.

TROLLEY-WHEEL.

1,391,085.

Specification of Letters Patent. Patented Sept. 20, 1921.

Application filed March 7, 1921. Serial No. 450,210.

To all whom it may concern:

Be it known that I, JOHN A. WENDELL, a citizen of the United States, residing at Montgomery, in the county of Fayette and State of West Virginia, have invented certain new and useful Improvements in Trolley-Wheels, of which the following is a specification, reference being had to the accompanying drawings.

10 This invention relates to improvements in trolley wheels, and more particularly to a trolley wheel in which the portions subjected to wear are readily removable.

An important object of the invention is to 15 provide a trolley wheel formed of separable sections one of which comprises a wear ring or ring which engages against the trolley wire so that the wear ring may be removed and replaced when it becomes worn.

20 A further object of the invention is to provide in a trolley wheel of the above mentioned character a bearing part upon which the trolley wheel rotates, which is likewise readily replaceable in the event of wear.

25 A still further object of the invention is to provide a novel construction of trolley wheel whereby the removal and renewal of worn sections may be accomplished with a minimum expenditure of labor.

30 Other objects and advantages of the invention will become apparent throughout the course of the following description.

In the accompanying drawings, wherein for the purpose of illustration is shown a 35 preferred embodiment of my invention, and wherein like reference characters designate like parts throughout:

Figure 1 is a side elevation of a trolley wheel constructed in according with my invention;

Fig. 2 is a sectional view taken therethrough;

Fig. 3 is a front elevation thereof;

Fig. 4 is a combined sectional view showing the side plates and wear plates separated, and

Fig. 5 is an inside face view of one of the side plates.

Referring now more particularly to the 50 drawings, the numeral 10 indicates a trolley head or wheel carrier embodying a shank 11 adapted for attachment to the trolley pole and having its upper end furcated to form spaced arms 12 which are apertured for the

reception of a pivot pin 13 preferably taking the form of a bolt.

The numeral 14 indicates duplicate side sections each of which is reduced on its inner face, as at 15, to form an annular shoulder, the side sections beyond the shoulder 60 being reduced in thickness toward the outer edges thereof.

Inwardly of the shoulder 15, each of the side sections is provided with an annular groove 16 upon its inner face with which 65 communicates a plurality of apertures 17 extending through the side member. The side members have a central bore 18 of greater diameter than the diameter of the bolt. These members when combined form 70 at their outer edge an annular groove adapted for the reception of a wear ring 19, which is wedge-shaped in cross section to coact with the side walls of the recess formed, and which is provided in its outer 75 face with a guiding groove 20 in which the trolley wire W runs. When the sections are assembled, a bushing 21 of less width than the combined widths of the side members 14 and having a driving fit in the bore 18 thereof is applied to the side members 75 to hold them in assembled relation, and the bushing 22 of the size to have a driving fit with the bolt 13 is arranged therein, the bushing 22 being of a length equal to the 80 combined widths of the side members 14. Between the bushings 21 and 22, anti-friction elements A are disposed and are held in position by means of washers 23 fitting 85 in the bore 18 of the side members and abutting the ends of the bushing 21, the washers having a bore rotatably receiving the ends 90 of the bushing 23. The annular groove 16 is combined to form an oil well which is in communication with the bearing thus 95 formed by means of radial openings 24 formed in the side members, or by a combination of grooves in the side members, and alining with openings 25 formed in the bushing 21.

It will be obvious that when the wheel is removed from the trolley head by removing the bolt 13, the side plates or washers 23 may be readily removed to inspect the bearings to ascertain whether or no the renewal 105 of the anti-friction elements A is necessary, or whether or no the bushings 21 and 22 are sufficiently worn to necessitate their re-

newal. Whether or no the wear ring 19 requires renewing may be readily determined by inspecting the outer face thereof and the renewal, if necessary, may be readily 5 made, as will be obvious.

From the foregoing it is believed to be obvious that I have constructed a trolley wheel which is particularly well adapted for the use for which it is intended by reason 10 of the fact that the parts thereof which are subjected to wear are so constructed that they may be readily removed and replaced, and by reason of the fact that the simplicity of the construction thereof enables ready 15 and economical manufacture of the device. It will furthermore be obvious that the construction as hereinabove set forth is capable of some change in modification without materially departing from the spirit of my invention, and I accordingly do not limit myself to the specific structure hereinabove set 20 forth except as hereinafter claimed.

What I claim:

1. In a trolley, a pair of duplicate side 25 members combining to form a wheel provided with a peripheral groove, an annular wear ring disposed within the groove, and an anti-friction bearing for said wheel embodying a bushing having a driving fit with said 30 side members and serving to hold said side members in assembled relation.

2. In a trolley, a pair of duplicate side members combining to form a wheel provided with a peripheral groove, an annular 35 wear ring disposed within the groove, and an anti-friction bearing for said wheel embodying a bushing having a driving fit with said side members and serving to hold said side members in assembled relation, said 40 side members being provided in coacting faces thereof with annular grooves combining to form an oil well, and having openings extending therethrough and in communication with the oil well forming grooves, 45 and alined openings formed in said bushing and side members, the last named openings of the said plates being likewise in communication with said oil well.

3. In a trolley, a trolley head adapted for 50 attachment to a trolley pole and furcated to form spaced arms, a pivot member extending through said arms, a wheel rotatably mounted upon said pivot member and comprising a pair of similar side members combining 55 to form in the periphery of the wheel a groove, an annular wear ring disposed within the groove, an anti-friction bearing for

said wheel embodying a bushing having a driving fit with the side members and serving to hold said side members in assembled 60 relation, a second bushing having a driving fit with said pivot member, and anti-friction elements disposed intermediate said bushings.

4. In a trolley, a trolley head adapted for 65 attachment to a trolley pole and furcated to form spaced arms, a pivot member extending through said arms, a wheel rotatably mounted upon said pivot member and comprising a pair of similar side members combining 70 to form in the periphery of the wheel a groove, an annular wear ring disposed within the groove, an anti-friction bearing for said wheel embodying a bushing having a driving fit with the side members and serving to hold said side members in assembled 75 relation, and a second bushing having a driving fit with said pivot member, and anti-friction elements disposed intermediate said bushing, the first named bushing being of 80 less width than the combined thickness of said side members, the bushing engaging said pivot member being of the same width as the combined thickness of the side members, and retaining washers rotatably mounted upon 85 the last named bushing and abutting the ends of the first named bushing.

5. In a trolley, a trolley head adapted for 90 attachment to a trolley pole and furcated to form spaced arms, a pivot member extending through said arms, a wheel rotatably mounted upon said pivot member and comprising a pair of similar side members combining to 95 form in the periphery of the wheel a groove, an annular wear ring disposed within the groove, an anti-friction bearing for said 100 wheel embodying a bushing having a driving fit with the side members and serving to hold said side members in assembled relation, a second bushing having a driving fit with said pivot member, and anti-friction elements disposed intermediate said bushings, said side members being provided in coacting faces thereof with annular grooves combining to form an oil well and having 105 openings extending therethrough and in communication with the oil well forming grooves, and alined openings formed in said bushing and side plates, the last named openings of the said plates being likewise 110 in communication with said oil well.

In testimony whereof I hereunto affix my signature.

JOHN A. WENDELL.
